CARBURETOR

Howard W. Linkert, Indianapolis, Ind., assignor,
by mesne assignments, to Marvel Carburetor
Company, Flint, Mich., a corporation of Illinois

Application April 2, 1930, Serial No. 440,906

15 Claims. (Cl. 261—34)

This invention relates to carburetors for internal combustion engines and has special reference to an improved type of plain tube carburetor.

5 It is an object of this invention to provide an improved carburetor of the class described which will supply an efficient and economical carbureted fuel and air mixture at various speeds and loads together with a richer mixture at maximum demand. Accordingly, my invention provides a plain tube carburetor having an idling fuel feed increasing in quantity as the throttle is opened and merging smoothly into the mixture supplied by the normal fuel 10 feeding system, which upon first coming into action is temporarily enriched by the emptying of a fuel well which thereupon becomes an air bleed connection to economize fuel under steady 15 operation at part throttle. Since the metering characteristics of an air bleed nozzle do not increase in step with an increased air flow as the throttle is further opened the normal accelerating pump fuel supply is so arranged as to feed into the main nozzle at higher 20 suction aside from its functions in providing a temporarily enriched mixture for accelerating 25 purposes.

It is another object of this invention to provide an improved accelerating pump structure 30 adapted to provide a delayed and prolonged fuel injection relative to the actuating movement of the pump linkage connected to the throttle. To this end, I provide a retarded lost motion connection between the pump and throttle to permit 35 minor movements of the throttle without actuation of the pump, and I prolong the period of pump discharge by providing a weighted follower above the piston which follower forces additional fuel into the main nozzle after the 40 piston stops moving to give the desirable follow up required for proper acceleration. The delayed flow, total amount and rate of initial and delayed flow can be regulated by properly proportioning the piston size, follower weight and 45 piston and outlet orifices.

It is another object of this invention to provide an improved and simplified plain tube carburetor with the minimum of moving or adjustable mechanisms, that will still vary the effective nozzle passage and discharge for economical 50 and maximum power conditions and wherein the effective nozzle passage varies according to the suction due to a supplementary fuel flow at high 55 suction.

Other and further important objects of this

invention will be apparent from the disclosures in the specification and the accompanying drawings.

This invention (in a preferred form) is illustrated in the drawings and hereinafter more fully described.

On the drawings:

Figure 1 is a plan view of a carburetor embodying the features of this invention.

Figure 2 is an elevational view from the air 65 inlet side thereof.

Figure 3 is a central vertical section on the line III—III of Figure 1.

Figure 4 is a partial section on the line IV—IV of Figure 2 showing the accelerating pump in 70 section with other parts in elevation.

Figure 5 is a section on the line V—V of Figure 3 showing the idling bypass and maximum-minimum fuel valve.

Figure 6 is a partly diagrammatic showing of 75 the carburetor, with the various fuel control devices transposed into a single plane.

As shown on the drawings:

The illustrated carburetor is of the plain tube type in which a single fixed venturi is used. 80 Normally all the air except that which passes through this fixed system passes through this fixed venturi. All the metered fuel, except the idle fuel and starting and warming up fuel, passes through a nozzle—whose tip extends into 85 the throat of the venturi and the fuel mixes at the throat of the venturi with the air passing through. There are no moving parts controlling the normal metering of the fuel except a maximum flow valve which is opened by the 90 throttle when the latter is opened wide and maximum power is desired at the expense of the more economical normal metering characteristics.

The carburetor body comprises an upper member 95 incorporating an outlet mixture passage 10, containing a throttle valve 11 on a shaft 12, and a cover 13 for a float bowl 14 in a lower member 15 containing an air inlet passage 16. The fixed venturi 17 is interposed between the 100 mixture outlet passage 10, and the air inlet passage 16. Fuel enters the float bowl 14 through an inlet 18 formed on the cover 13, the admission of the fuel being regulated by a float 19.

The main fuel nozzle 20 is fed in three ways from the float bowl. First, the normal requirements flow from the bowl through inlet ports into a metering pin housing 21 containing a double diameter metering pin 22, which in in its 110

normal upper position restricts the fuel flow downwardly in its housing past an orifice 23 therein, thence out of the housing into a passage 24 leading to a nozzle chamber 25 at the base of the nozzle 20. The metering pin projects through the cover 13 into a position to be depressed by an arm 26 provided on the accelerating pump operating link 27 when the throttle is opened to its full extent. The depression of the metering pin brings the smaller diameter thereof into position in the orifice 23 thus increasing the effective area of the orifice to increase the flow of fuel.

A throttle operated accelerating pump is provided, the cylinder 28 of which, is fed fuel from the float chamber through a passage 29 and non-return valve 30. From the pump cylinder a discharge passage 31 leads into a plug 32 inserted in the lower end of the nozzle chamber 25 and containing a ball check valve 33. This plug carries a restricted or accelerating discharge nozzle 34 extending upwardly within the main nozzle passage 35. Besides furnishing extra fuel when the throttle is being opened, the accelerating system above described supplements the regular fuel supply passing through the main nozzle under high suction conditions. When the throttle is held nearly constant fuel enters the pump cylinder through the non-return valve and thence into the nozzle through the accelerating nozzle 34.

The third source of fuel supply to the main nozzle is formed as an auxiliary adjustment in order to insure very close factory flow bench settings for individual carburetors. This comprises a high speed needle valve 37 controlling the admission of fuel to a passage 38 leading into the nozzle chamber 25. This needle valve allows a small amount of fuel to be fed past it into the nozzle system. The metering pin 22 is purposely made to give a slightly leaner mixture than desired and the extra fuel required to give a proper mixture is fed past the high speed valve 37. In practice this valve is set at the factory and adjustment thereafter is unnecessary except for great changes in general operating conditions, as at high altitudes.

In plain tube carburetors it is necessary to supply fuel, for operation under idling conditions, above the throttle disc when closed, because under such conditions the air flow through the venturi is so slight that it will not pick up fuel from the main nozzle. The idle fuel is taken out of the main nozzle through a passage 39 leading from an annular chamber 40 formed in the shank of the main nozzle and communicating with the passage therethrough. An idle tube 41 has calibrated restrictions in both ends and the lower end is threaded into the passage 39. The upper end of the tube discharges into a passage 42 where it is mixed with air from a passage 43. The mixture of fuel and air then passes into a small chamber 44 and is discharged into the carburetor mixture outlet passage above the edge of the closed throttle disc through an orifice 45. A second passage 46 is positioned below the edge of the closed throttle disc and serves as an air bleed into the chamber 44 under such circumstances. When the throttle is increasingly opened from its extreme closed or idling position the lower passage 46 is gradually exposed to the suction above the throttle and then delivers mixture from the chamber 44 to supplement the delivery from the upper passage or orifice 45. In this way an

increased flow of fuel passes through the idle system as the throttle is opened, until the main nozzle starts to deliver. The two idle discharge passages thus supplement each other and graduate smoothly into the normal nozzle discharge. 80

An idling adjustment is provided comprising a needle valve 48 controlling the admission of air from the passage 43 into the passage 42. By increasing the admission of air the suction on the idling tube is decreased thus thinning the idling mixture, and by decreasing the inflow of air this suction will be increased thus increasing the delivery of fuel from the idling tube. 85

The main fuel nozzle 20 is of the air bleed type wherein air bleed holes 49 are formed in the nozzle at different elevations and are fed air from a well 50 surrounding the lower part of the idle tube. The top of the well 50 opens into an air inlet passage 51 extending down to the lower edge of the venturi and consequently 95 drawing air from the main air inlet passage of the carburetor. The passage 51 also supplies the idle air passage 43.

When the carburetor is full of fuel the well 50 contains fuel and this condition holds true 100 under idling conditions up until the main nozzle starts to deliver. When the nozzle starts to deliver due to opening of the throttle the fuel in the well 50 flows through the uppermost air bleed holes 49 into the nozzle 20. As the air flow 105 through the venturi increases the remainder of the fuel in the nozzle chamber about the air bleed holes 49 flows through the lower air bleed hole into the nozzle. As soon as the fuel is out of the well 50 and the passage connecting the 110 well to the nozzle chamber, air bleeds into the nozzle chamber 25 and thence through the air bleed holes 49 into the nozzle passage 35.

The throttle operated accelerating pump comprises a piston 52 operable in the cylinder 28, 115 the piston having an upstanding stem 53 projecting through the cover 13 and having a lost motion connection 54 to the link 27, which incorporates the maximum-minimum metering pin operating arm 26, and which is pivoted to 120 the end of a lever 56 secured to the throttle shaft. A friction spring 57 acts against the stem 53 to take up the lost motion slack in such a way as to delay the movement of the accelerating pump in response to both opening and 125 closing movements of the throttle. The combination of the lost motion connection and friction spring holds the stem at any one position and allows the movement of the throttle to be reversed to the extent of the lost motion before 130 the pump starts to operate. If, for example, a vehicle be allowed to coast, the well 50 fills with fuel and upon opening up from the idling position used for coasting the well 50 will deliver first followed by the accelerating pump if the 135 throttle is opened sufficiently. Another feature of this lost motion connection and friction retarding device is to allow small throttle changes, such as occur when driving cross-country, on medium rough roads, without waste of fuel by 140 the accelerating pump.

The accelerating pump also incorporates a delayed or prolonged delivery after the cessation of the downward movement of the pump piston. This is accomplished by providing a weighted 145 follower 58 surrounding the stem above the piston. A port 59 through the piston permits a portion of the fuel to enter between the follower and the piston during the downward movement of the piston and after the cessation of piston 150

movement the weight of the follower forces the fuel back through the piston port 59 and out through the pump delivery passages leading to the main nozzle.

5 The air inlet passage 16 is provided with a choke valve disc 60 loosely mounted on a shaft 61 offset relative to a principal diameter of the passage to form an unbalanced valve. The choke valve disc is driven by the shaft through a lost 10 motion connection afforded by the projection of a pin 62 through a limited slot 63 in that portion of the valve enveloping the shaft. A spring 64 normally holds the valve advanced relative to the shaft so that the operation of the shaft 15 through the usual dash control acting on a lever 65, will resiliently close the valve by approximately a three quarters movement of the dash control, and the further final movement of the control will take up the lost motion and thus 20 hold the valve rigidly closed. When the valve is only resiliently closed the unbalanced condition thereof causes it to automatically open in response to the suction of the engine, thus providing a yielding choke which facilitates starting 25 under normal conditions, the rigid choke being required only for abnormally severe conditions.

In the operation of this carburetor the idling fuel supply is metered in accordance with the throttle position which regulates the demand. 30 The idling fuel thus increases in proportion to the throttle opening until the flow of air through the venturi is sufficient to start delivery from the main nozzle, the transition point being well covered by the overlapping of delivery from the 35 idling and main nozzle. When the main nozzle starts delivery the well 50 first empties through the nozzle and is followed by the delayed and prolonged accelerating pump discharge thus giving a temporarily enriched mixture to meet 40 engine accelerating requirements. Under normal operation the well 50 will have been emptied and will then act as an air bleed into the main nozzle as previously described. If the demand on the engine increases short of wide open throttle 45 the increased suction on the nozzle will start additional flow of fuel thereto through the accelerating pump passages, the increased suction being sufficient to cause the flow of fuel past the non-return valves in these passages. The 50 auxiliary needle valve serves to supplement the intentionally lean metering of the fuel supply as previously described, and thus compensates for manufacturing variations in individual carburetors.

55 The foregoing metering characteristics are so proportioned as to provide an economical mixture ratio up to practically full open throttle conditions. When maximum power is desired, a richer mixture is needed and is obtained by 60 the final opening movement of the throttle acting to depress the maximum-minimum metering pin to increase the effective area of the orifice 23. The last stage of the throttle opening movement has relatively slight effect in increasing 65 the effective opening in the case of a butterfly throttle but by utilizing this movement to open the maximum metering pin a substantial increase in power output is obtained.

The resilient choke structure also serves to 70 enrich the metering characteristics throughout the normal range, when such an adjustment is desirable due to operating conditions by increasing the carburetor suction under given conditions of load and speed and thus increasing 75 the flow of fuel relative to the volume of enter-

ing air. The suction imposed on the choke valve tends to open the same thus limiting the increase in suction so obtainable unless the choke is rigidly closed.

It will thus be seen that I have invented an improved carburetor of the class described incorporating improved fuel metering characteristics for normal and maximum power together with accelerating means supplementing the normal metering means.

I am aware that many changes may be made and numerous details of construction may be varied through a wide range without departing from the principles of this invention, and I therefore do not purpose limiting the patent 85 granted hereon otherwise than necessitated by the prior art.

I claim as my invention:

1. In a carburetor a nozzle, means for providing a metered fuel supply thereto, a fuel well which when emptied forms an air bleed into said nozzle, a throttle valve, an accelerating pump discharging into said nozzle, a lost motion connection from said throttle to said accelerating pump for operating the pump after a predetermined movement of the throttle, and frictional retarding means associated with said pump for taking up the slack in said lost motion connection in each direction opposite to the movement of the throttle.

2. In combination with a throttle controlled carburetor, an accelerating device comprising fuel pumping means including a chamber and a reciprocable piston therein, a lost motion connection between said throttle and said piston for controlling the movement of said piston, a weighted follower reciprocable in said chamber above said piston, and a means for introducing fuel between said piston and follower upon pumping action of said piston, whereby said follower will return said fuel and prolong the discharge of said accelerating device after the cessation of motion of said piston.

3. In combination with a throttle controlled carburetor, an accelerating device comprising fuel pumping means including a chamber and a reciprocable piston therein, a lost motion connection between said throttle and said piston for controlling the movement of said piston, and a frictional retarding device for holding back 120 said piston to the limit of the slack in said lost motion connection in a direction opposite the last movement thereof.

4. In combination with a throttle controlled plain tube carburetor including a fuel chamber and an air bleed type of fuel discharge nozzle in communication therewith, an accelerating device comprising fuel pumping means, a separate connection between the fuel chamber and the nozzle and subject to suction thereon for supplementing the normal fuel supply to said nozzle, a valve in said connection adapted to open under high suction conditions, and a connection between said throttle and said pumping means including a lost motion link for retarding the responsiveness of said fuel pumping means.

5. In combination with a throttle controlled plain tube carburetor including a fuel chamber and an air bleed type of fuel discharge nozzle in communication therewith, an accelerating device comprising fuel pumping means, a separate connection between the fuel chamber and the nozzle for supplementing the normal fuel supply to said nozzle under high suction conditions, and a connection between said throttle 145

- and said pumping means including a lost motion link for retarding the responsiveness of said fuel pumping means, and friction means engaging said connection momentarily maintains 5 the slack in the lost motion link upon reversal of the motion of said connection.
6. In combination with a throttle controlled plain tube carburetor including a fuel chamber and an air bleed type of fuel discharge nozzle 10 in communication therewith, an accelerating device comprising fuel pumping means, a separate connection between the fuel chamber and the nozzle for supplementing the normal fuel supply to said nozzle under high suction conditions, 15 and a connection between said throttle and said pumping means including a lost motion link for retarding the responsiveness of said fuel pumping means, and means in said fuel pumping means for prolonging the discharge of fuel therefrom 20 after cessation of motion of the connection between the throttle and the pumping means.
7. In combination with a throttle controlled plain tube carburetor including a fuel chamber and an air bleed type of fuel discharge nozzle in 25 communication therewith, an accelerating device comprising fuel pumping means, a separate connection between the fuel chamber and the nozzle for supplementing the normal fuel supply to said nozzle under high suction conditions, and 30 a connection between said throttle and said pumping means including a lost motion link for retarding the responsiveness of said fuel pumping means, and friction means engaging said connection momentarily maintains the slack in the lost motion link upon reversal of the motion of said connection, and means in said fuel pumping means for prolonging the discharge of fuel therefrom after cessation of motion of the connection between the throttle and the pumping 35 means.
8. In combination with a carburetor including a throttle, an accelerating device associated with said carburetor and including a cylinder, a piston in said cylinder having an operating 40 connection to said throttle, a weighted cylindrical element independently movable in said cylinder above said piston, a fluid port through said piston whereby the pumping operation of said piston discharges a portion of the fuel above 45 the piston and beneath the weighted element, said weighted element thereby serving to return the fuel so discharged after the cessation of the pumping motion of said piston to prolong the discharge period of said accelerating device.
- 50 9. In combination with a carburetor including a throttle, an accelerating device associated with said carburetor and including a cylinder, a piston in said cylinder having an operating connection to said throttle, said operating connection having a lost motion link therein to reduce the responsiveness of the accelerating device at small throttle movements, and retarding means for said operating connection to hold back the operation of said device to the limit of the slack 55 therein.
10. In a plain tube carburetor including a throttle, an air bleed fuel nozzle, means supplying fuel directly thereto, a fuel pump discharging into said nozzle, fuel supply passages 60 to and from said pump so arranged as to form a secondary source of fuel supply to said nozzle at high suctions when the pump is inoperative, a suction responsive valve normally closing said passages and means for operating said pump 65 from said throttle, including means for retard- 70 ing the initial responsiveness of said pump to throttle movements in either direction.
11. In a plain tube carburetor including a throttle, an air bleed fuel nozzle, means supplying fuel directly thereto, a fuel pump discharging into said nozzle, fuel supply passages to and from said pump so arranged as to form a secondary source of fuel supply to said nozzle at high suctions when the pump is inoperative and means for operating said pump from said throttle, and means associated with said pump for retarding the delivery of a portion of the fuel displaced by said pump until after the cessation of the pump stroke, whereby to prolong the fuel discharge for an interval after the pump has 75 ceased its motion. 80
12. In a plain tube carburetor including a throttle, an air bleed fuel nozzle, means supplying fuel directly thereto, a fuel pump discharging into said nozzle, fuel supply passages to and from said pump so arranged as to form a secondary source of fuel supply to said nozzle at high suctions when the pump is inoperative and means for operating said pump from said throttle, including means for retarding the responsiveness of said pump to throttle movements, and means associated with said pump for retarding the delivery of a portion of the fuel displaced by said pump until after the cessation of the pump stroke, whereby to prolong the fuel discharge 90 for an interval after the pump has ceased its motion. 95
13. In a carburetor including a throttle, an accelerating device associated with the carburetor and including a cylinder, a piston in said cylinder having a sliding fit therewith, a stem projecting upwardly from said piston and having an operating connection with the throttle, a weighted annular element independently movable in said cylinder above said piston and having a sliding fit with said stem and said cylinder, and a fluid port through said piston whereby the downward stroke of said piston forces a portion of the fuel above the piston and beneath the weighted element, said weighted element falling by gravity after completion of the downward stroke of the piston to force out the fuel from between the element and the piston to prolong the discharge period of said accelerating device. 100 110
14. In a carburetor, a throttle, a fuel nozzle discharging into the carburetor, means supplying fuel directly to the nozzle and a device for supplying additional fuel to said nozzle for accelerating purposes comprising a cylinder, a piston in said cylinder having a sliding fit therewith to form a first fuel discharging means, a positive mechanical connection between said throttle and said piston to effect a downward discharge movement thereof upon opening movement of said throttle, a second discharge means comprising a second piston coaxial with said first piston, and an annular surface on said first piston engaging said second piston to support the same in inoperative position, said second piston falling by gravity after release by downward discharging movement of said first piston to discharge additional fuel to the nozzle and thereby extend the period of accelerating supply after the first piston has ceased its movement. 120 125
15. In a plain tube carburetor, a throttle, an air bleed fuel nozzle, means supplying fuel directly thereto, and a device for supplying additional fuel to said nozzle for accelerating purposes comprising a first cylinder and piston 130 135 140 145 150

means having a relatively slidable fit, a positive mechanical connection between said throttle and the piston of said means to actuate the same in accordance with the movement of said throttle, 5 and a second cylinder and piston means coaxial with said first means and associated therewith in a manner to be held thereby in inoperative

position, said second means operating by gravity after release by discharge movement of said first means to discharge fuel and thereby extend the period of discharge after the first means has ceased its movement.
